US00D940310S

(12) **United States Design Patent** (10) Patent No.: **US D940,310 S**
de la Rama et al. (45) Date of Patent: ** Jan. 4, 2022

(54) **HIGH DENSITY CATHETER TIP**

(71) Applicant: **ST. JUDE MEDICAL,
CARDIOLOGY DIVISION, INC.**, St. Paul, MN (US)

(72) Inventors: **Alan de la Rama**, Cerritos, CA (US); **Cary Hata**, Irvine, CA (US); **Don Curtis Deno**, Andover, MN (US); **Carlo Pappone**, Cernusco Lombardone (IT)

(73) Assignee: **ST. JUDE MEDICAL,
CARDIOLOGY DIVISION, INC.**, St. Paul, MN (US)

(**) Term: **15 Years**

(21) Appl. No.: **29/759,859**

(22) Filed: **Nov. 25, 2020**

Related U.S. Application Data

(63) Continuation of application No. 16/670,678, filed on Oct. 31, 2019, which is a continuation of application No. 14/760,682, filed on Jul. 13, 2015, now Pat. No. 10,492,729.

CLAIM

The ornamental design for a high density catheter tip, as shown and described.

DESCRIPTION

FIG. 1 is a top plan view of a high density catheter tip showing our new design;

FIG. 2 is a side perspective view thereof; and,

FIG. 3 is a side elevation view thereof in a flexed position. The dashed broken lines and stipple shading shown in the side elevation view in FIG. 3 illustrates a surface that forms no part of the claimed design. The dot-dash broken lines in the drawings define the boundaries of the claimed design and form no part thereof. The remaining dashed broken lines in the figures depict portions of the catheter tip that form no part of the claimed design.

1 Claim, 3 Drawing Sheets
